UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

SEALING MECHANISM FOR WINDOW FRAMES AND SASHES.

Application filed June 24, 1927. Serial No. 201,119.

In various of my patents, such for example as Patent No. 1,459,711, I illustrate a form of window structure in which the jambs are provided with vertical openings in their inner faces, which lead into enlarged chambers within the jambs. The sashes have plates which extend through the openings into the jambs and are supported by sash chains which are attached to the plates within the chambers and run over pulleys that are positioned near the tops of the jambs, and from the pulleys extend into the weight chamber.

The present invention is based upon my discovery that such a construction will result in a very substantial leakage through the window unless particular provision is made to meet it. This leakage is due to the fact that cold air will enter the outer chamber through the vertical opening below the upper sash, will pass upwardly around the sides of the sash plate in the outer chamber, thence through the pulley holes around the sash chain into the weight chamber. From the weight chamber the air will travel through the pulley holes that lead to the inner chamber for the lower sash, and from this chamber into the room through the inner vertical opening above the lower sash.

The present application contains matter derived from my earlier applications Serial No. 696,141 filed March 1, 1924, and Serial No. 165,526, filed February 3, 1927.

The use of the enlarged chambers into which the sash plate extends is advantageous as forming an air cushion against sudden increases in pressure and as reducing the velocity of air that may tend to leak around the sash. Accordingly, it is undesirable to fill these chambers to prevent the leakage referred to. I have found that it is possible to prevent this leakage by forming a stop in the outer chamber which will limit or substantially eliminate the passage of air up around the outer sash to the chain holes, but which will not materially interfere with the operation of the sash or fill up the outer chamber to eliminate the advantages that ensue from its substantial size.

Various methods in which this can be accomplished (all of which are closely related) are illustrated in the accompanying drawings, in which Fig. 1 is a sectional view through a portion of a jamb; Fig. 2 is a

sectional view through a meeting rail of a window showing the face of the jamb with a part broken away, illustrating the same form of device as shown in Fig. 1. In these figures the device is intended to be positioned in the outer chamber near the bottom of the upper sash; Fig. 3 is a sectional view similar to Fig. 1 showing a modified form of construction which may be placed at any desired point in the outer chamber along the upper sash; Fig. 4 is a face view of the structure shown in Fig. 3 with a part of the cover broken away; Fig. 5 is an alternative form of construction adapted to be used with the stop mechanism located below the upper sash but carried by it. The position on which this section is taken is indicated by the line 5—5 of Fig. 3, though the parts are not the same as those shown in Fig. 3; Fig. 6 is a horizontal sectional view showing a form of device intended to be located near the top of the upper sash; Fig. 7 is a vertical sectional view of the parts shown in Fig. 6, and Fig. 8 is a vertical sectional view corresponding to Fig. 7 showing a still further modification.

As described in my Patent No. 1,549,711 the jamb comprises a hook-shaped member 3 with a short leg 4 which forms a portion of the inner jamb wall and a longer leg 5 which forms a partition within the jamb. A baffle 6 is attached to leg 5 of member 3 with a space between the baffle 6 and the short leg 4, leaving a vertical opening which leads into an enlarged chamber which for the purposes of convenience will be referred to as the "outer chamber." The upper sash is provided with plates 8 which extend through such vertical openings into the outer chambers. As the parts thus far described are common to all the modifications herein illustrated, the same reference letters will be applied to them throughout. The usual structure of the balance of the jambs and sash are illustrated in the patent referred to.

Referring to Figs. 1 and 2, I am able substantially to stop the vertical movement of air in the outer chamber by inserting in the outer chamber adjacent the middle of the window, two blocks 10 and 12 which will make approximate sliding contact with the plate 8 of the upper sash. These blocks may be made of solid material but I prefer to

make them of resilient material such as felt, so that they may actually rub against the sides of the plate 8.

It is necessary that the form of plug illustrated in Figs. 1 and 2 be placed near the middle of the window as no provision is made for the chain to pass through between the blocks. If it is desired to place these blocks higher up in the jamb, an opening 10 has to be provided through which the chain may pass, and means must be supplied for closing this opening. Such a form of construction is illustrated in Figs. 3 and 4 where the blocks 14 and 16 are cut out to 15 form a substantially round opening 18 through which the sash chain 20 may pass. Attached to the sides of the plate 8 are two angles 21 and 22 which are adapted to press against the lower faces of blocks 14 and 16 20 when the upper sash is closed, thereby closing the opening 18.

In Fig. 5 I show a device which is adapted to move with the upper sash. This comprises a block 24 of such shape as substantially to fill a cross-sectional portion of the outer chamber and make sliding contact with the walls thereof. This block should preferably be made of resilient material such for example as felt. The block is attached to the plate 8, but in order to prevent the block from limiting the freedom of movement of the upper sash, the connection between the plate and the block consists of a pair of links 26 which are pivoted to the 30 plate by a pin 28, which preferably should fit loosely in the hole provided in the plate 8. By this arrangement, the block 24 will move with the upper sash but the upper sash will not be unduly restricted as to either 35 transverse movement or movement in and out of the room.

When the means for limiting vertical movement of air in the outer chamber are positioned near the bottom of the upper sash, there is always the possibility that any cold air which may leak into the outer chamber between the sash plate 8 and leg 4 of member 3 will find its way into the room through the chain holes. Accordingly I prefer to correct this defect by a device 45 positioned near the top of the outer chamber as illustrated, for example, in Figs. 6, 7 and 8.

In Figs. 6 and 7, the plate 8 of the upper 50 sash is shown as cut away at the upper corner to clear the pulley wheel 30. Positioned in the outer chamber just above the shoulder thus formed in plate 8 is a block 32 provided with a conical opening 34. In the detail here shown the block 32 is also provided with a slot 35 to receive the edge of plate 8 which extends above this block. The sash chain 20 is provided with plug 36 which fills the conical opening 34. It is preferable that 60 one of the members 32 or 36 be made of re-

silient material and as here illustrated the block 32 is intended to represent felt.

In Fig. 8 I show a modification where a metal plate 38 is substituted for the block 32 of Figs. 6 and 7. In this case the sash 70 chain is provided with a readily compressible stop 40 which may be made, for example, of sponge rubber and slipped over the chain. When the upper sash is raised to its closed position the block 40 will press 75 against the plate 38 and be squeezed against the chain 20 as well as closing up the hole through the plate 38.

It is to be understood that the foregoing examples are given by way of illustration 80 only and that many other modifications may be made.

What I claim is:

1. In a window-frame and sash construction comprising jambs having vertical openings for the upper sash leading into enlarged chambers which are connected to passages leading to another part of the jamb, an upper sash with portions extending through said vertical openings into said chambers, and sash suspension members attached to the upper sash in such chambers and running thence to another part of the jamb through said passages; partition members 90 for such chambers positioned below said 95 passages and adapted when the upper sash is closed to contact with movable sash members and thereby limit vertical movement of air in such chambers up around the upper sash and into such passages. 100

2. In a window-frame and sash construction comprising jambs having vertical openings for the upper sash leading into enlarged chambers which are connected to passages leading to another part of the jamb, an upper sash with portions extending through said vertical openings into said chambers, and sash suspension members attached to the upper sash in such chambers and running thence to another part of the jamb through said passages; members movable with the upper sash adapted to contact with jamb members when the upper sash is closed, substantially to fill relatively short sectional portions of such chambers adjacent the upper sash and thereby limit vertical movement of air in such chambers up around the upper sash and into such passages. 110 115

3. In a window-frame and sash construction comprising jambs having vertical openings for the upper sash leading into enlarged chambers which are connected to passages leading to another part of the jamb, an upper sash with portions extending through said vertical openings into said 120 chambers, and sash suspension members attached to the upper sash in such chambers and running thence to another part of the jamb through said passages; means for limiting vertical movement of air in such chambers 125

bers consisting of members adapted, when the upper sash is closed, substantially to fill relatively short sectional portions of such chambers adjacent the upper sash.

- 5 4. In a window-frame and sash construction comprising jambs having vertical openings for the upper sash leading into enlarged chambers which are connected to passages leading to another part of the jamb,
- 10 an upper sash with portions extending through said vertical openings into said chambers, and sash suspension members attached to the upper sash in such chambers and running thence to another part of the
- 15 jamb through said passages; partition members for said chambers positioned below said passages and members movable with the upper sash adapted, when the upper sash is closed, to contact with said partition members
- 20 in a substantially horizontal plane.
- 5. A combination as specified in claim 4 in which one pair of said contacting members is compressible.
- 6. A combination as specified in claim 4, in which the partition members are located near the top of said chambers and the members movable with the sash are compressible.
- 25 7. A combination as specified in claim 4, in which the members movable with the sash are readily compressible members surrounding the sash chain.

8. In a window of the type having jambs, openings through the inner walls of the jambs, a parting strip forming part of the inner jamb wall between such openings, separate enlarged chambers back of such openings and sashes having plates adapted to extend through such openings, pulley wheels connected by openings with said chambers, a stop plate closing the chambers for the upper sash near the tops thereof with holes for the pulley chain, chains attached to the sashes and members carried by said chains adapted to close said holes when the upper sash is closed. 45

9. A window construction comprising jambs having vertical openings in their inner walls, chambers in each of said jambs back of each of said openings, sashes adapted to slide in said openings and having portions adapted to extend into said chambers, and partition members in two of said chambers adapted when the window is closed to contact with sash members for a small proportion of the height of such sashes and substantially to close said chambers, whereby an air space is left adjacent the edge of such sash for the greater part of its height but vertical movement of air in such chambers is limited. 50 55
